UNITED STATES PATENT OFFICE

148,299

DESIGN FOR A TRACTOR

Milton T. Hedquist and James Haley, Rock Island,
Ill., assignors to J. I. Case Company, Racine,
Wis., a corporation of Wisconsin

Application June 29, 1946, Serial No. 131,162

Term of patent 7 years

(Cl. D14—3)

To all whom it may concern:

Be it known that we, Milton T. Hedquist and James Haley, citizens of the United States, residing at Rock Island, in the county of Rock Island and State of Illinois, have invented a new, original, and ornamental Design for a Tractor, of which the following is a specification, reference being had to the accompanying drawing, forming a part thereof, in which:

Fig. 1 is a perspective view of a tractor embodying our new design taken from one side and forwardly thereof;

Fig. 2 is a perspective view taken from directly in front and slightly above the tractor shown in Fig. 1; and

Fig. 3 is a perspective view taken from the rear end slightly above the tractor.

The characterizing features of our new design are shown in full lines in the drawing.

We claim:

The ornamental design for a tractor, substantially as shown and described.

MILTON T. HEDQUIST.
JAMES HALEY.
